UNITED STATES PATENT OFFICE

OTTO A. GIEFFEN, OF NEWARK, OHIO

BROODER

Application filed December 2, 1929. Serial No. 410,933.

This invention relates to brooding systems for poultry and is particularly directed to that class of brooders known as "colony brooders" and which derive their heat from a central heating system. This invention has for its principal object the provision of a brooder in which the proper temperature is maintained at all times within the hover while at the same time an adequate supply of fresh air is maintained within the hover and proper ventilation of the hover is insured thereby adding to the efficiency of the brooder and eliminating those dangers attendant upon the use of hovers in which the chicks are crowded in unventilated areas.

A further object of the invention resides in the provision of a brooder in which the hover may be raised and the entire floor space under the hover exposed thereby permitting the hovers to be thoroughly cleaned and maintained in a sanitary condition.

A still further object of the invention resides in the provision of a brooder provided with a plurality of hovers and so arranged that the use of any one or more of the hovers may be discontinued and the floor space occupied by them rendered available for other purposes without in any degree affecting the efficiency or operation of the remaining hovers.

With these and other objects in view which will appear as the description proceeds, the invention consists in the novel features of construction, combination of elements and arrangement of parts hereinafter to be more fully described and pointed out in the appended claims.

In the accompanying drawings:

Figure 1 is a horizontal sectional view of my improved brooder showing in plan the hovers and central heating system,

Figure 2 is a vertical sectional view taken on the line 2-2 of Figure 1,

Figure 3 is a horizontal sectional view taken on the line 3-3 of Figure 2,

Figure 4 is a sectional view taken on the line 4-4 of Figure 2,

Figure 5 is a vertical sectional view of my improved brooder taken on the line 5-5 of Figure 2,

Figure 6 is a vertical sectional view taken on the line 6-6 of Figure 1, and

Figure 7 is a partial elevation of the swinging gates as shown by the line 7-7 of Figure 1.

55

Referring more particularly to the drawings, the numeral 1 represents my improved brooder in its entirety which includes end walls 2 and 3, a front wall 4 and a rear wall 5, which walls are formed to include the 60 usual windows 6 and door 7. At the end of the brooder 1 is provided a boiler room 8 which is separated from the brooder room 9 by the wall 10. The floor 11 of the brooder room 9 is formed preferably from concrete 65 although any suitable flooring may be employed and is constructed so as to slope toward that portion of the building containing the boiler room. Inside the brooder and adjacent the rear wall 5 is provided a longitudinally extending pit 12, one edge of the 70 floor 11 terminating at the top of the inner wall 13 of the pit. I prefer to form the pit 12 so that its bottom wall 14 is approximately 2 feet below the plane of the floor 11 and extends in a plane parallel thereto. I prefer 75 also that the floor of the boiler room 8 be not higher than the bottom wall 14 of the pit. The pit 12 extends the full length of the brooder room 9 and is separated from 80 the boiler room 8 by the wall 10.

Adjacent the wall 5 and at right angles thereto are positioned vertically extending spaced partitions 15, each having one edge suitably secured to the wall 5 and one edge 85 resting on and suitably secured to the floor 11 and extending into the room 9 a sufficient distance to provide the space adjacent the pit and wall 5 and between the walls 10 and 3 into a suitable number of hover areas 16. 90 Each partition 15 extends downwardly into the pit 12 so as to meet each of the walls thereof thereby dividing the pit 12 into areas corresponding in width to the hover areas or spaces. I prefer to employ partitions 15 95 extending vertically to the ceiling although they may be employed of a lesser height. In each hover area there is supported vertically within the pit 12 a partition 17. The partition 17 is formed preferably from an in-

sulating material and is positioned parallel to and approximately equidistant from the side walls of the pit. Each partition 17 extends the full width of the hover area and 5 its vertical ends are suitably secured to the wall or partition defining the limitations of the hover area as shown in Figure 3. The partition 17 extends from $1\frac{1}{2}$ to 2 feet above the plane of the floor 11 and its lower edge 10 18 is spaced from the bottom wall 14 of the pit.

The partition 17 is supported in its position by means of spaced vertically extending members 19 which are in turn secured to the 15 wall 5. The members 19 extend vertically from the bottom wall 14 of the pit to the top of the partition 17 thereby dividing the space between the partition 17 and the wall 5 into a plurality of air ducts 20 and preventing 20 lateral movement of air within the area between the partitions 17 and the wall 5. I have found it very satisfactory to employ in a structure of this character a pit of approximately 12 inches in width with the 25 partition so spaced that the air ducts 20 are approximately 6 inches in width. It will be understood, of course, that the dimensions may be varied without departing from the spirit of my invention.

30 Secured to the partition 17 is a horizontally extending shelf or deflector 21, its free edge 22 being above and spaced from the edge of the floor 11. The shelf 21 extends the full width of the hover area and serves 35 to define the upper limit of the heating chamber 23. If desired the spaced dividing members 24 may be employed within the heating chamber 23 extending vertically from the bottom wall 14 of the pit to a point at 40 or near the level of the floor 11 so as to prevent lateral movement of the air within the chamber 23.

Within each hover area is provided a 45 hover 25 which extends the full width of the hover area 16 as defined by the partitions or walls and comprises a top portion 26 and front portion 27. The top portion 26 of the hover is hinged at one edge to the deflector, as at 28, and extends normally outwardly 50 and upwardly. The front portion 27 of the hover is hinged to the top portion as at 29 so that the front portion during the operation of the hover always remains vertical. The hover is supported in its operating position 55 by a chain or rope 30 which is secured at one end to the top of the hover near its outer edge as at 31 and passed over a friction pulley 32 secured to the roof of the brooder 1. A weight 33 may be attached to the free end 60 of the chain so as to counterbalance the weight of the hover 25. By means of this arrangement not only is the hover 25 supported in its proper operating position but it may be maintained in any desired position of vertical adjustment. The portions 26 and 27 of

the hover are formed to include an inner portion 34 of insulating material with an outer covering 35 of suitable metal.

A back wall 36 is suitably fastened to the top of the floor 11 with one face of the wall 36 in approximately the same plane as the inner face of the inner wall 13 of the pit. The wall 36 extends longitudinally the entire width of each hover and its upper edge 37 is spaced from the lower side of the deflector 21 as shown in Figure 2. I have found in practice that with the lower edge of the deflector 21 approximately 6 inches above the top of the floor 11, the back wall 36 should be approximately $3\frac{1}{2}$ inches in height. The opening 38 between the top of the back wall and the deflector is covered with a wire mesh or screen 39. Attached to the upper edge of the wall 36 by hinges 40 is a door 41 which serves when desired to completely close the opening 38 thereby preventing communication between the heating chamber 23 and the area under the hover 25.

Suitably positioned in the boiler room 8 is a boiler 42. By means of the pipe 41 hot water is circulated from the boiler through a plurality of pipes 44 and is returned to the boiler by way of the pipe 45. The plurality of pipes 44 extend longitudinally the full length of the brooder room 9 and are positioned between the partition 17 and the inner wall 13 of the pit, each pipe in a plane parallel to the plane of the surface of the floor level. Each of the pipes 44 is passed through suitable openings in the wall 10, the partitions 15 and the dividing members 24 so that the pipes 44 extend through each of the heating chambers 23. An automatic regulator 46 may be employed for controlling the temperature of the water in the boiler in accordance with the temperatures desired under the hovers 25.

It will be seen that in my improved brooder the cool air passes downwardly in the duct 20 between the wall 5 and the partition 17, then under the lower edge of the partition 17, then upwardly through the heating chamber 23 between the partition 17 and the inner wall 13 where the temperature of the air is raised to the desired degree by reason of the pipes 44 receiving hot water from the boiler 42. As the heated air passes upward it strikes the deflector 21 and passes through the opening 38 into the space under the hover 25. As the air under the hover 25 is cooled it passes out from under the hover by way of the space 47 beneath the front portion 27 and is immediately replaced by fresh warm air coming from the heating chamber 23 by way of the opening 38. My improved brooder not only insures adequate ventilation for the area under the hover but insures that the entire floor area under the hover will always be warm since the cool air immediately passes out from under the hover. The distribution

of heat under the hover 25 is further assisted by the metallic portion 35 on the under side of the hover which tends to reflect the heat downwardly. My improved brooder therefore, not only provides an improved heating system which results in the uniform heating of the whole area but provides for ventilation for the chicks while under the hover which is of the utmost importance particularly in brooders where large numbers of chicks are confined at one time as is usual in the case of commercial poultry raising.

The hover 25 being hinged at one edge may be adjusted so as to vary the height of the space 47 thereby enabling the hover to more properly accommodate chicks of varying ages. Not only is this adjustment possible but the hover 25 may be entirely folded back against the wall 5 as shown in Figure 2, thereby removing all obstructions to the floor under the hover and rendering the same easily accessible for cleaning thereby facilitating those sanitary measures which are essential in the successful rearing of young chicks. It will also be observed that when the brooding season is over and the hover is no longer required to be used the same may be folded back as shown in Figure 2, against the wall and all of the floor space of the floor 11 is made available for whatever purpose is found most desirable. My improved brooder is so constructed that where a plurality of hovers are employed the use of any one or more of the hovers may be discontinued without in any manner affecting the efficiency of the remaining hovers. When it is desired to discontinue the use of a particular hover the hover 25 is folded against the wall 4, as shown in Figure 2, and the door 41 is retained by a suitable fastener. The closing of the opening 38 prevents the escape of the heated air from the heating chamber 23 and the partition 15 which extends to the bottom of the pit 12 prevents any lateral movement of air into the adjoining hover thereby permitting the remaining hovers to function undisturbed.

In order to prevent the chicks confined in the brooder from gaining access to the top of the hover 25 I have provided panels or gates 48 which are arranged in pair for each hover. Each gate is formed preferably to include an angularly bent rod having a vertical portion 49 received within spaced eyebolts 50, as at 51. Suspended from the horizontal portion 52 of the rod by suitable members 53 is a panel of wire mesh or hardware cloth. The gates 48 are so positioned that the lower edge of each gate is parallel to and adjacent the upper edge of the front portion 27 when the hover 25 is in its lowermost position. One of the gates comprising each pair is provided with a latch 54 which may be engaged with the corresponding horizontal member of the opposite gate so as to retain the gates against swinging movement when in position. It

will be seen that the gates in no way interfere with the adjustment of the hover and when it is desired to raise the hover 25 for the purpose of clearing the gates may be swung outwardly as shown in Figure 1. They may also be lifted upward, thus freeing them from the eyebolts 50 thereby making it possible to quickly remove the gates for storage when the hover is not being used. Since the gates are made from wire mesh they will afford no obstruction to the passage of light and will not interfere with the proper circulation of air within the brooder.

Positioned against the under side of the floor 11 and extending throughout the entire length thereof are a plurality of horizontally spaced pipes 55 which are connected with the boiler 42 by means of the hot water pipe 56 and the return pipe 57. The number of the pipes 55 may be varied in accordance with the materials of which the floor 4 is constructed but I prefer always to have one of the pipes 55 positioned under the floor 11 at a point beneath the hover 25. By means of this construction hot water from the boiler 42 is circulated through the pipes 55 thus warming the floor 11 and thereby preventing the condensation of moisture on the floor which invariably results when warm air within a brooder contacts with the floor. This is especially true when the floor 11 is formed from concrete or similar material. Since moisture is the common cause of most poultry diseases, particularly in young chicks, I have provided a dry floor thereby eliminating those causes and insuring a sanitary and unusually healthful brooder. A warm dry floor also tends to eliminate floor drafts thereby adding to the efficiency of my brooder. It will be understood, of course, that the temperature of the water in the pipes 55 should only be sufficient to warm the floor 11 and prevent the accumulation of moisture thereon and for that reason the temperature of the water in the pipes 55 may be maintained lower than the temperature of the water in the pipes 44 or the boiler. I therefore provide means for reducing the temperature of the water coming from the boiler before it enters the pipes 55. Connecting the hot water pipe 56 and the return pipe 57 is a bypass pipe 58 in which are located valves 59 and 60. The pipe 61 serving as an intake for an electrically operated centrifugal pump 62 is connected with the pipe 58 between the valves 59 and 60. A discharge pipe 63 connects the pump 62 with the pipe 56. The valve 64 is positioned in the pipe 56 between the boiler and the connection with the pipe 55. It will thus be seen that when the valves 59 and 60 are closed and the valve 64 is open the water from the boiler 42 is circulated through the pipes 55 by means of a thermo-siphon system. By closing the valve 64, partially opening valves 59 and 60 and operating

the centrifugal pump 62 a certain amount of cooled water from the return pipe 57 is drawn into the pump and mingles with a certain amount of hot water from the boiler 42 so that the temperature of the water entering the pipes 55 by way of pipes 56 and 63 is thereby reduced. By manipulating the valves 59 and 60 and operating the pump 62 the water entering the pipes 55 may be cooled to the temperature desired. By closing the valves 60 and 64, opening the valve 59 and operating the pump 62 a forced system is established for circulating the water through the pipes 55. It will be understood that in the operation of this system the pump 62 may be operated periodically or continuously, as desired.

In order to maintain the air within the brooder room 9 at the desired temperature during all seasons of the year I prefer to employ a plurality of horizontally extending pipes 65 adjacent the wall which are secured to the wall 5 at a point some distance above the floor level 11. The pipes 65 are connected with the boiler 42 by means of the pipes 66 and 67 whereby hot water from the boiler is circulated through the pipes 65 thereby heating the air in the room 9 to the desired temperature. A valve 68 is provided in the pipe 66 for regulating the rate of flow of water in the pipes 65 or for shutting it off altogether when desired.

What is claimed is:

1. A brooder structure formed to comprise a longitudinally extending pit adjacent one wall and along one edge of the floor of said structure, a partition supported vertically within said pit approximately equi-distant from the side walls thereof and extending both above and below the plane of the floor of said structure and spaced from the floor of said pit, a horizontally extending shelf positioned against the inner side of said partition, said shelf extending above the inner half of said pit and having its free edge above and spaced from said floor edge, a hover hingedly connected with the free edge of said shelf and extending outwardly and upwardly therefrom, a member positioned on said floor above the inner wall of said pit, the upper edge of said member being spaced from the under side of said shelf, and a plurality of hot water pipes positioned in said pit between the inner wall thereof and said partition.

2. A brooder structure formed to include a longitudinally extending pit adjacent one wall and along one edge of the floor of said structure, a longitudinally extending partition supported above the floor of said pit and spaced from the side walls thereof, and extending above and below the plane of said floor, a shelf positioned against said partition and having one edge above and spaced from the edge of said floor, a plurality of

vertically extending laterally spaced partitions positioned on said floor so as to divide the floor adjacent said pit into hover spaces, a plurality of hovers, each of said hovers being arranged in one of said hover spaces, each hover being hinged at one edge to said shelf and normally extending above said floor, adjustable means for maintaining the free edge of each of said hovers at a desired elevation, a plurality of longitudinally up-standing members, each member extending upwardly from the edge of the floor in one of said hover spaces, the upper edge of each of said members being spaced from said shelf so as to form a passage in each of said hovers, a plurality of hot water pipes extending longitudinally of said pit and positioned below each of said shelves for causing warm air to circulate under each of said hovers by way of said passages, means associated with each of said members for closing each of said passages, and means for preventing the lateral movement of air in said pit.

In testimony whereof I affix my signature.
